ROLL PAPER CUTTER

Kenneth A. Van Dyck, Rochester, N. Y., assignor
to Eastman Kodak Company, Rochester, N. Y.,
a corporation of New Jersey

Application November 9, 1949, Serial No. 5,944

Term of patent 14 years

(Cl. D61—1)

To all whom it may concern:

Be it known that I, Kenneth A. Van Dyck, a citizen of the United States of America, residing in Rochester, in the county of Monroe and State of New York, have invented a new, original, and ornamental Design for a Roll Paper Cutter, of which the following is a specification, reference being had to the drawing, forming a part thereof in which:

Fig. 1 is a perspective view taken from the rear and slightly above and to one end of the roll paper cutter showing my new design; and

Fig. 2 is a perspective view thereof taken from the front and slightly above and from the opposite end of the roll paper cutter.

I claim:

The ornamental design for a roll paper cutter, as shown.

KENNETH A. VAN DYCK.
